UNITED STATES PATENT OFFICE.

ERNEST L. BURKETT, OF GREENSBOROUGH, VICTORIA, AUSTRALIA, ASSIGNOR OF ONE-HALF TO SIMON JOSEPH, OF MELBOURNE, VICTORIA, AUSTRALIA.

SLIDING SASH WINDOW.

Application filed June 29, 1921. Serial No. 481,307.

To all whom it may concern:

Be it known that I, ERNEST LEE BURKETT, carpenter, a subject of the King of Great Britain and Ireland, and a resident of the 5 post town of Greensborough, in the shire of Heidelberg, county of Evelyn, State of Victoria, Commonwealth of Australia (whose post-office address is Main Road, in the said post town of Greensborough), have invented 10 certain new and useful Improvements in and Connected with Sliding Sash Windows, of which the following is a specification.

This invention relates to sliding sash windows and its primary object is to dispense 15 with the usual ropes or cords and pulleys at present employed to connect the balance weights with the sashes in such windows. Thus the well known disadvantages, such for 20 instance as the breaking of the weight cords, attendant upon the use of such devices, is overcome.

The invention is simple, inexpensive and efficient and contains no parts liable to derangement. Furthermore, it may be fitted 25 without difficulty to existing as well as to new windows.

Referring to the drawings which form part of this specification:—

Figure 1 is a part sectional front view of 30 the invention.

Figure 2 is a vertical section through the window frame the sashes being removed to show the toothed wheels in the stiles.

Figure 3 is a cross section on line A—A of 35 Figure 1.

Figure 4 is a perspective view of one of the bearings for the toothed wheels.

Figure 5 is a plan of said bearing.

Figure 6 is a perspective view of a window sash according to the invention.

Figure 7 is a perspective view of a balance weight in accordance with the invention.

Figure 8 is a side view showing a modified 45 construction of the rack on the side of the sash.

Figure 9 is a part sectional front view of Figure 8.

In the drawings, the numeral 2 indicates 50 the window frame which is provided with the usual inner or front beads 3, outer beads 4 and intermediate beads 6 whereby the inner and outer sashes 7 and 8 are guided in their sliding movement along the stiles 9.

55 Formed within the window frame and be-

hind the stiles 9 are the weight passageways 11 the two said passageways on each side of the window being separated by the partitions 12.

According to the invention there is formed 60 through each of the stiles 9 and approximately at the mid-length thereof, an opening 13. Into this opening fits a bracket or bearing which is preferably constructed as shown in Figures 4 and 5 and comprises two 65 opposite side cheeks 14 having bosses 16 within which are formed open mouthed gullets 17. The bearings are also provided with flanges 19 in which are holes 21 to accommodate screws 22 whereby the bearings are secured to the stiles with the side cheeks 14 disposed in the openings 13.

Accommodated in the opposite slots 17 of each bearing is the axle 23 of a toothed or sprocket wheel 24, the teeth of said wheels 70 projecting into the weight passages 11 and also outwardly through the openings 13 in the stiles as in Figure 1. It will be evident from the foregoing that the open mouthed slots 17 of the bearings permit of the toothed 75 wheels being readily placed in and removed from the bearings when the sash is removed.

In conjunction with the foregoing a toothed rack 26 is carried preferably on each side of each of the window sashes. 80 These racks may be constructed of metal, fibre, or other suitable material and may be let into vertical grooves 27 formed in the sides of the sashes as shown. Said racks are adapted to engage the toothed wheels 24 85 in the window frame. Two of said racks and toothed wheels are preferably provided for each sash although it will be evident that the invention is capable of operation with a rack and toothed wheel on one side 90 of the sash only.

Formed at the lower end of each sliding sash and on the inner side thereof are rebates or recesses 28 which are adapted to pass over the projecting parts of the toothed 100 wheels 24 to permit of the sashes being readily introduced into the upper part of the window frame and the racks 26 engaged with the toothed wheels.

Accommodated within each of the weight 105 passage-ways is an elongated balance weight 29 of metal or other suitable material and having along one of its vertical faces a toothed rack 31. The racks of these balance weights engage the toothed wheels 24 in 110

the adjacent stiles 9 as shown so that by movement of the sash in one direction the balance weights thereof are caused to slide in an opposite direction by rotation of the toothed wheels, thus acting to balance or control the movement of the sashes and to retain them in any desired position.

It will be evident that the length and weight of each balance weight 29 will depend upon the length or height and weight of the corresponding sash the weights forming a sliding fit in the weight passages. Each balance weight may, if desired, be provided with pockets or cavities 32 to hold shot or the like whereby the weights may be rendered heavier or lighter according to requirements.

In a modification as seen in Figures 8 and 9 a vertical groove 33 is formed in each 20 side of the window sash and is covered by a sheet metal plate 34 screwed or otherwise attached to the side of the sash. Apertures 36 are formed through that portion of the plate 34 which is disposed over the groove 33 these apertures being preferably formed by stamping or punching from the sheet metal thus producing inwardly projecting tongues 37 which may abut against the bottom of the groove 33 as shown and thus 30 effectively reinforce the plate and form a resting surface for engagement with the teeth of the wheels 24 which project through the apertures 36. This form of rack may be simply and cheaply made and provides 35 a strong and light construction.

In operation, as the sash is moved downwardly or upwardly the racks thereon rotate the toothed wheels which in turn cause the balance weights engaging them to slide 40 up or down along the weight passageways in the opposite direction to the movement of the sash.

It will be evident from the foregoing that the toothed balance weights act to retard or control the sliding movement of the sashes without the employment of cords or ropes and pulleys as at present, thus rendering the structure immune from derangement through breakage of such cords or fouling 45 of the pulleys.

The particular construction and arrangement of parts described and illustrated may obviously be altered or modified in various respects and additional appurtenances or refinements may be introduced without departing from the spirit and scope of the invention.

Having now described my invention what I claim as new and desire to secure by Letters Patent is:—

A bracket adapted to fit in an opening formed approximately mid-length the central beading of a sliding sash window, said bracket being of plate formation with a central gear-receiving opening having its side walls extended outwardly with respect to the window sash, said walls being recessed to receive a supporting shaft, the recesses opening through the face of the bracket, and to the gear receiving opening, a supporting shaft mounted in said recesses and limited in movement toward the rear of the bracket and freely movable toward the face of the bracket, a gear mounted on said shaft and extended in both directions beyond the bracket, and gear racks adapted to be secured to the window sash and operating weight therefor, said racks being simultaneously and reversely operated in the movement of the gear.

In testimony whereof I affix my signature.
E. L. BURKETT.

Witness:

JACK NANCE.
